INSULATOR.

1,198,131.

Specification of Letters Patent. Patented Sept. 12, 1916.

Application filed October 2, 1914. Serial No. 864,562

To all whom it may concern:

Be it known that I, RAY P. JACKSON, a citizen of the United States, and a resident of Edgewood Park, in the county of Allegheny and State of Pennsylvania, have invented a new and useful Improvement in Insulators, of which the following is a specification.

My invention relates to electrical insulating bodies or structures, and it has special reference to insulators which are adapted for outdoor installation and exposure to severe mechanical and electrical service conditions.

At present, the usual insulators are made entirely of unprotected porcelain members which are nested into one another and cemented together. This type of construction necessarily makes such insulators fragile and liable to breakage when subjected to severe mechanical shocks. Moreover, it is practically impossible to repair these whole porcelain insulators when one of the nested porcelain pieces becomes cracked or ruptured, because of the difficulty in replacing it with a new member without breaking the remaining porcelain members to which the defective member is securely cemented. Also, whole porcelain insulators usually depend for their insulating properties upon long leakage paths between the conductors that are to be insulated and the ground. Consequently, portions of such insulators are subjected to abnormal electrical stresses resulting from the concentrations thereupon of the electrostatic lines which comprise the electric fields existing between the conductors to be insulated and the ground, and which surround the insulators. If provision can be made for distributing the electrostatic lines substantially uniformly upon the surfaces of the porcelain insulators to preclude concentrations thereupon of abnormally high electrical stresses, the insulators may be safely utilized for higher voltages than has heretofore been deemed advisable.

One object of my invention is to provide an insulator comprising members of porcelain or some other material of high dielectric strength, which members are so disposed as to provide a built-up structure but wherein the members may be easily replaced when any one of them becomes defective, without requiring the whole insula-

tor to be scrapped or the conductor, which is insulated, to be disconnected from the insulator while making replacements of the injured insulating members.

Another object of my invention is to provide an insulating structure that is particularly adapted for severe service conditions by affording protection to the fragile portions, which usually constitute the insulating portions, against mechanical blows.

A further object of my invention is to provide an insulator which may be used for very high-voltage service conditions for the reason that its insulating portions will not be subjected to abnormal concentrations of electrostatic stresses.

Other features of novelty will be described and pointed out in the following specification and appended claims to which reference may now be had.

Figure 1 is a view, partially in elevation and partially in section, of an insulator embodying a form of my invention, and Fig. 2 is a cross-sectional view of a modified form of the insulator shown in Fig. 1.

Referring to Fig. 1, the insulator comprises a plurality of superposed insulating members 1, which are preferably made of porcelain, and metallic supports 2 that provide caps 3 which embrace top portions 4 of the members 1. Each support 2 is also provided with an upwardly extending portion 5 which projects into a recess formed in the top portion 4 of the porcelain member 1 located above it. Bodies of cement 6 hold each porcelain member 1 firmly between the extending portion 5 of one support 2 and the portion 3 of the next succeeding support. In this manner, a rigid structure is secured by means of which considerable weight may be supported. A metallic cap 7 is disposed on the top porcelain member 8 and is provided with a connector 9 to which an electrical conductor, which it is desired to insulate, may be connected. A support 10 of any desirable construction provides means for securing the built-up structure to the tower or pole on which it may be mounted.

The insulating members 1 are shaped preferably as shown in the drawing, being provided, at their lower ends, with conically flared petticoats. The members 1 being made of fragile material, such as porcelain, are

capable of withstanding compressive stresses only and, therefore, they are interposed between portions of the metallic members 2 which resist the main mechanical stresses imposed upon the insulating structure. Inasmuch as the porcelain members 1 resist all the electrical stresses imposed upon the structure, they are liable to breakage because of flash-overs and mechanical 10 defects which are greatly exaggerated when the porcelain members are subjected to electrical stresses.

To insure a substantially uniform distribution of electrostatic stresses upon the 15 insulator shown in Fig. 1 (as will be herein-after described), metallic petticoats are provided on the metallic supports 2, such as are indicated at 19^a. It will be apparent that the metallic petticoats 19^a afford protection 20 to the insulating members 1 also against mechanical blows. As a result, insulators made in accordance with my invention may be installed where the mechanical and electrical service conditions are very severe.

25 In Fig. 2, metallic supports 12, which are interposed between adjacent porcelain members 1, comprise two detachable portions 13 and 14. The upper portion 13, which projects into the recess formed in the upper portion 4 of the insulating member 1 and which is secured thereto by the cement 6, is provided, at its lower periphery, with a flange or a plurality of spaced lugs 15. The lower portion 14 of the support 12 embodies 30 a cap 16 which embraces the upper portion 4 of the next succeeding lower insulating member 1. A flange 17, integrally formed on the portion 14, provides a seat for the flange 15. Bolts 18 firmly hold the portions 35 13 and 14 together, thereby insuring a rigid structure.

40 It is apparent that, when a member 1 becomes defective, it may be detached from the structure by removing the bolts 18 which 45 engage with the supports 12 immediately above and below the defective insulating member. In this manner, defective insulating members may be expeditiously and conveniently replaced by new insulating members 50 without affecting either the electrical or the mechanical properties of the built-up structure. Moreover, it is unnecessary, during such replacing of operations, to disconnect the conductor 9 from the support.

55 I prefer that each of the metallic members 12 be provided with conically flared portions 19 which constitute a series of superposed metallic petticoats that alternate with the superposed insulating members 1. As 60 a result, a series of condensers is supplied, the conducting plates constituting the petticoats 19 and the dielectric between adjacent conducting plates comprising the porcelain members 1. Inasmuch as the petticoats 19 65 conform substantially in shape to the petti-

coats of the insulating members 1, a uniform distribution of the electrostatic lines surrounding the built-up insulator is assured. It is well known that, if concentrations of electrostatic stresses are precluded from 70 forming upon the insulating members 1, the insulating members may be used to their full insulating value and, consequently, the built-up structure may be subjected to voltages which would otherwise have been impossible 75 without the use of the metallic petticoats 19.

While I have shown and described several embodiments of my invention, it will be understood that many modifications may be made without departing from the spirit 80 thereof, and I desire that its scope shall be limited only by the appended claims.

I claim as my invention:

1. An insulator comprising a plurality of superposed insulating members having outwardly-flared petticoats, and metallic supports therefor which are interposed between, and rigidly secured to, adjacent insulating members, said supports being provided with portions that conform substantially to the 85 shape of said flared portions of the insulating members.

2. An insulator comprising a plurality of superposed and similarly shaped insulating members which are conically flared, and rigid metallic supports interposed therebetween and secured to adjacent insulating members, said metallic supports being provided with conically flared portions which 90 conform in shape substantially to that of the conically-flared portions of the insulating members.

3. An insulator comprising a plurality of superposed insulating members having flared petticoat portions, and metallic supports interposed therebetween and secured to adjacent insulating members, said metallic supports being provided with petticoat portions which conform in shape substantially to those of said insulating members in order to insure a substantially uniform 105 distribution of electrostatic stresses upon the surfaces of the insulating members.

4. An insulator comprising an insulating 110 member which is conically flared, and metallic members disposed above and below said insulating member, said metallic members being provided with conically flared portions which are so shaped as to conform 115 substantially to the shape of corresponding portions of said insulating member thereby precluding concentrations of electrostatic stress upon the insulator.

5. An insulator comprising a plurality of 120 superposed insulating members, and metallic supports interposed between adjacent members, said rigid metallic supports comprising upper portions which engage the 125 upper insulating members and lower por-

tions which engage the lower insulating members, the two portions of each support being exteriorly detachable.

6. An insulator comprising a plurality of superposed insulating members and rigid metallic supports interposed therebetween which are nested within one another and engage the upper portions of said insulating members in order to subject them to compressive stresses, each metallic support comprising two exteriorly detachable portions, the upper one engaging the upper insulating member and the lower one engaging the lower insulating member.
- 15 7. An insulator comprising a plurality of superposed insulating members and rigid metallic supports interposed therebetween which are nested within one another and engage the upper portions of said insulating members in order to subject them to compressive stresses, each metallic support being provided with a portion that conforms substantially to the shape of the insulating

members and comprising two exteriorly detachable portions, the upper one engaging 25 the upper insulating member and the lower one engaging the lower insulating member.

8. An insulator comprising a plurality of superposed insulating members and rigid metallic supports interposed therebetween, 30 each metallic support comprising two exteriorly detachable portions, the upper one engaging the upper insulating member and being nested within the lower portion of the next succeeding upper support and the lower one engaging the lower insulating member and embracing the upper portion of the next 35 succeeding lower support.

In testimony whereof, I have hereunto subscribed my name this 25th day of Sept., 40 1914.

RAY P. JACKSON.
